LATCH MECHANISM

Filed Aug. 10, 1927

INVENTOR.
George Halinka.

BY
Thomas J. Donnelly
ATTORNEY.

UNITED STATES PATENT OFFICE

GEORGE HALINKA, OF DETROIT, MICHIGAN

LATCH MECHANISM

Application filed August 10, 1927. Serial No. 211,873.

My invention relates to a new and useful improvement in a latch mechanism adapted particularly for mounting on doors and other bodies supported swingably on a suitable support.

It is an object of the present invention to provide a latch mechanism whereby the latch may be moved to inoperative or releasing position through the operation of a cam upon the pulling outwardly of the operating member.

It is another object of the invention to provide a latch mechanism of this class whereby the latch mechanism may be moved to inoperative or releasing position from either side of the door with which used, so arranged that the releasing mechanism on one side of the door will not interfere with the operation of the cam operated mechanism at the other side of the door and so that the cam operated mechanism will not prevent the movement of the latching mechanism to inoperative position from the other side.

Another object of the invention is the provision of a latch mechanism of this class whereby a retractable member may be directly withdrawn for moving the latch mechanism to inoperative position.

Another object of the invention is the provision of a latch mechanism operable from either side of the door with which used, so arranged and constructed that the operating mechanism at one side of the door may be removed considerably from location of the operating mechanism at the other side.

Other objects will appear hereinafter.

The invention consists in the combination and arrangement of parts hereinafter described and claimed.

The invention will be best understood by a reference to the accompanying drawings which form a part of this specification and in which,

Fig. 1 is a central sectional view through the invention showing it applied to a door.

Fig. 2 is a view taken on line 2—2 of Fig. 1.

Fig. 3 is a view taken on line 3—3 of Fig. 2.

Fig. 4 is a view taken on line 4—4 of Fig. 1.

Fig. 5 is a fragmentary top plan view of the invention.

In the drawings, I have illustrated the invention applied to a door 9 swingably mounted in relation to the support 10 upon which is mounted the wear plate 11 having the offset portion 12 set into the recess 13 formed in the support 10 and provided with the offset portion 14 to serve as an auxiliary engaging portion for the latch bolt 15 which is slidably mounted in a recess 16 formed in the door 9.

Mounted on the door 9 and extending into the recess 16 is a bracket comprising the side walls 17 and 18 connected by the cross bar 19 in which is formed the opening 20 to accommodate the pin or plunger 21 which projects into a recess 22 formed in the latch bolt 15, this plunger 21 being pinned or otherwise secured in the recess or socket 22. As clearly appears from Fig. 1, the latch bolt 15 is cut away to provide the recess 23. Engaging in this recess 23 is a roller 24 mounted on a shaft 25 which extends through the side plates 26 and 27, each of these side plates being pivotally mounted at its lower end to the side walls 17 and 18 of the bracket. Carried by the side plates intermediate the ends thereof is a roller 28. Positioned in embracing relation upon the plunger 21 is a spiral spring 29, one end of which engages the cross bar 19, and the other end of which engages the socket bearing end of the latch member 15.

A passage 30 is formed in the door and projects through the outer face thereof, this passage 30 communicating at its inner end, which is flared, with the recess 16. Extending into the passage 30 is a bushing 31 having a head 32 formed thereon. A handle 33 is provided from which the stem 34 projects, this stem extending through the head 32 and passing through the bushing 31 and engaging at its inner end in a socket 35 of a cam bolt 36, this stem 34 being secured in said socket. The cam bolt 36 is cut away as at 37 to provide a recess in which engages the roller 28, the inclined surface of the cam bolt 36 which extends upwardly from the base of the recess 37 serving to operate as a cam.

A screw 38 is provided for retaining the bushing 31 in position. Positioned about the stem 34 and engaging in the bushing 31 is a spiral spring 39 which engages at one end

the head 32 and at the other end the outer end of the cam bolt 36.

In operation, after the door has been closed, a movement of the handle 33 into the position shown in dotted lines in Fig. 1 will effect a movement of the cam bolt 36 into the position shown in dotted lines in Fig. 1, thus causing the roller 38 to ride on the inclined surface mentioned and rocking the plates 26 and 27 on their pivots. The roller 24 engaging in the recess 23, will thus move the latch bolt 15 into retracted position shown in dotted lines in Fig. 1, this movement effecting a compressing of the springs 29 and 39 so that the latch mechanism is released and the door may be swung to open position.

On the inner side of the door 9 I have mounted a handle 40 at one end of which I have pivoted a push member comprising a bell crank 41 normally held in outwardly pressed position by the spring 42, this spring engaging in a housing or cup shaped recess 43 formed on the handle 40. A hook 44 is formed on the roller end of the bell crank 41, this end projecting through a slot 45 formed in the bar 46, this bar being pivotally connected to a bar 47 which is connected by the screw 48 to the latch bolt 15. Thus, by rocking the bell crank 41, which may be effected from the inside of the door 9 by an inward pressure on the bell crank, the bar 46 being moved longitudinally to retract the latch bolt 15 to withdrawn or inoperative position.

Projected into the recess 16 formed in the door 9 is a shaft 49 provided on the inner side of the door 9 with the operating handle 50 whereby this shaft may be rocked at will, the shaft 49 being journaled in the bearing 51 formed on the side wall 18 of the bracket. Fixedly mounted on the lower end of the shaft 49 is a locking finger 52 adapted when moved to inoperative position for projecting into the recess 53 and when moved to operative position as shown in dotted lines in Fig. 4 to engage behind the plates 26 and 27 and lock the latch bolt 15 against movement to inoperative position. In this manner I have provided a latch mechanism whereby a pulling may effect through a cam operation the release or movement of the latch mechanism from operative to inoperative position. I have also provided a push mechanism which may be at a distance from the pull member whereby the latch may be released and moved to inoperative position.

While I have illustrated and described the preferred form of my invention, I do not wish to limit myself to the precise details of structure shown, but desire to avail myself of such variations and modifications as come within the scope of the appended claims.

Having thus described my invention what I claim as new and desire to secure by Letters Patent is:

1. A latch mechanism of the class described, comprising: a latch bolt slidably mounted; a pull member; a cam on said pull member; and means engageable with said cam for moving said latch member to inoperative position upon the outward pulling of said pull member; and a push member on the opposite side of the door with which used, adapted, upon pushing, for moving said latch member to inoperative position, said cam engaging means being arranged to permit the movement of said latch bolt to inoperative position without disturbance of said pull member. 70

2. A latch mechanism of the class described, comprising: a slidably mounted latch bolt; a pull member; a cam movable upon outward pulling of said pull member; and a lever engageable by said cam for moving said latch bolt to inoperative position upon outward pulling of said pull member; and a push member adapted upon pushing, for moving said latch bolt to inoperative position, neither said pull member nor said push member effecting operation of the other. 80 85

3. A latch mechanism of the class described, comprising: a latch bolt slidably mounted; a pull member; a cam on said pull member; an engagement member projecting laterally from said latch bolt and engageable with said cam upon movement of said pull member axially, the axial movement of said pull member effecting axial movement of said latch bolt; a guide member; and a pin projecting from one end of said latch bolt and 90 extending through said guide member. 95

In testimony whereof I have signed the foregoing specification.

GEORGE HALINKA.
